UNITED STATES PATENT OFFICE.

JAMES A. JOHNSTON, OF SEATTLE, WASHINGTON, ASSIGNOR OF TWENTY PER CENT.
TO THOMAS J. CLAFFEY AND FIVE PER CENT. TO NICHOLAS AMBROSE, BOTH OF
CHICAGO, ILLINOIS.

TOILET-FIXTURE CONNECTION.

1,389,004.

Specification of Letters Patent. Patented Aug. 30, 1921.

Application filed January 21, 1920. Serial No. 352,919.

To all whom it may concern:

Be it known that I, JAMES A. JOHNSTON, a citizen of the United States, and resident of the city of Seattle, in the county of King 5 and State of Washington, have invented certain new and useful Improvements in Toilet-Fixture Connections, of which the following is a specification.

My invention relates particularly to water 10 closet drain connections.

The object of my invention is to provide a toilet fixture drain connection which is capable of being tightly sealed in both the toilet and the drain pipe so that there is no 15 possibility of leakage of drain water or sewer gas, and which will form a connection in which the parts will not become separated and leak after a period of use.

Another object of my invention is to provide 20 a connection of the character described which will be sufficiently flexible to admit some variation in spacing between the intake end of the drain pipe and the outlet of the toilet fixture.

Another object of my invention is to provide 25 a water closet fixture, which would generally be made of porcelain, in such a shape that it will not need to be provided with a projecting outlet pipe, which is liable to be broken in shipment, in the forms now in use.

My invention comprises the novel parts and combinations thereof which are shown in the accompanying drawings, described in the specification, and particularly defined 35 by the claims.

In the accompanying drawings I have shown my invention in its present preferred forms.

Figure 1 is a sectional view through a portion 40 of a toilet fixture and the drain pipe showing the manner of securing my connection in place.

Fig. 2 is a similar sectional view of a slight modification of construction.

Fig. 3 is a sectional view showing another 45 modification.

In the style of water closet connections now in use the connection of the water closet with the drain pipe or soil pipe, after a 50 short period of use, becomes loose and permits leakage of drain water and of sewer gas. Partially this fault is due to the materials used in the packing gaskets, and it is partially due to the form of connection 55 with the water closet and the drain pipe.

In fitting such a fixture into a house it is difficult to put in the drain pipe in such a manner that its end will exactly register with or approximately touch the outlet of the water closet fixture, or to hold it in such a way that a reasonably tight joint may be made between them. There is certain to be a variation in the separation between the outlet of the water closet fixture and the opening of the drain pipe in any two installations. To provide for this variation and to insure permanently tight joints both with the drain pipe and with the water closet fixture I have provided the type of connection shown and described in this application.

The water closet 1 may be of any suitable construction except that about its outlet 10 I form in it a deep annular groove 11. I prefer also that the lower end of the outlet 15 should not project below the level of the floor flange 12. The soil pipe or drain pipe 2 is bent upwardly where it is intended to be connected with the toilet fixture, and about its upper end 20 is formed a collar 21. Preferably the collar 21 would be outside of the upturned end 20 of the drain pipe, thus forming between itself and the end 20, an annular groove 22.

In fitting such a fixture in the house the drain pipe 2 is first secured with its end 20 beneath the position which will be occupied by the outlet 10 of the fixture 1. A separate pipe section or floor connection 3 is employed to connect the drain pipe with the toilet fixture. The pipe section 3 comprises a floor flange 32, an upper sleeve 30, and a lower sleeve 31. The lower sleeve 31 is constructed of a size to fit within the collar 21 of the drain pipe 2 to form a snug fit with one side of the groove 22. As shown in Fig. 1, and as I prefer to make it, the snug fit is between the sleeve 31 and the collar 21. The collar 21 should be spaced from the end 20 of the pipe enough to permit

pouring of a sealing material between the sleeve 31 and the end 20 after the pipe section 3 is in place. The groove 22 should be deep enough to permit considerable variation in the position of the lower end of the sleeve 31 therein. This permits variation in the spacing between the end 20 of the drain pipe and the outlet 10 of the fixture 1 to be taken care of in fitting the fixture in a house.

After the sleeve 31 is fitted into the collar 110

21 a suitable seal, preferably of poured metal, as lead, may be poured from the inside of the pipe section 3 and will occupy the space as shown at 33 beneath the sleeve 5 31 and between this sleeve and the end 20 of the drain pipe. This seal, in the preferred construction, may be poured from above, through the pipe section 3, making it possible for the plumber to see what he is 10 doing, and greatly facilitating the work. The fit between the sleeve 31 and collar 21 is tight enough to prevent leakage of the metal being poured.

The floor flange 32 of the pipe section 3 15 may be secured to the floor before sealing the sleeve 31 in the groove 22, as by means of screws 34. After the section 3 has been secured to the drain pipe the toilet fixture 1 may be secured in place upon it. The 20 upper sleeve 30 is adapted to form a close fit within the groove 11 about the outlet of the toilet fixture. The sleeve 30 should be of such a length that its upper end comes nearly to the bottom of the groove 11. The 25 remainder of the space may be filled with any suitable form of gasket, as shown at 35. I prefer that this gasket should be made of a resilient, but non-shrinking material. I have found compositions known as litharge 30 and glycerin, or lubricated asbestos, to be suitable for the use intended.

The gasket 35 serves to securely seal the connection against sewer gas and should be of a material that will not deteriorate, 35 shrink or break with use. However, if such matter is not used, by making the groove 11 very deep and the fit of the sleeve 30 therein a close one, a relatively inefficient gasket at 35 will serve to seal in the sewer gas. Also 40 the construction of the groove 11 serves to prevent leakage of the drain water, as the water will not be under sufficient pressure to force itself up between the sleeve and groove.

45 The fixture may be secured to the section 3 by means of bolts 13 or to the floor by means of the bolts 14. After it has been placed upon the sleeve 30 with the gasket 35 resting upon the upper end of the sleeve 50 30 the pipe section 3 and the fitting 1 should be pressed together to compress the gasket 35 and to cause it to fill the available space at the upper end of the sleeve 30.

The connection thus described forms a 55 joint which is tight and secure against drain water and sewer gas both in its connection with the toilet fitting and with the drain pipe. The connection with the drain pipe is of such character as to permit variation 60 in the position of the upper end of the pipe and to facilitate its installation. In addition, the pouring of the seal 33 from the inside of the pipe connection 3 without any packing between the sleeve 31 and the collar 21 permits a quicker and easier sealing

of this connection from above, where, if it were to be sealed from below, it would be difficult to pour the metal into this collar on account of the interference with the floor above. Where there is more room in which 70 to work, however, the outside seal may be found more satisfactory, as shown in Fig. 3.

In Fig. 2 I have shown a construction which is similar to the construction just described, with the exception that the lower 75 sleeve 31 of the pipe connection 3 is screwed into the upper end 23 of the drain pipe 2 and no collar similar to the collar 21 is employed upon the upper end of the drain pipe. This connection, however, is not so 80 flexible as the one just described, and the former is my preferred construction.

What I claim as my invention is:

1. A water closet drain connection comprising a water closet having a deep annular 85 groove in its base extending about and separate from its outlet, a drain pipe, and a pipe section adapted to be secured to the floor and having its upper end closely fitting within said groove in the water closet, 90 a collar formed about the end of the drain pipe and forming therewith an upwardly facing annular groove, the lower end of the pipe section fitting closely within the inner side of said collar to form a tight joint, and 95 a seal of poured metal filling the remainder of said annular groove beneath the lower end of the pipe section and between the pipe section and the drain pipe, and a gasket compressed between the upper end of said 100 pipe section and the bottom of the groove in the closet base to form a gas-tight joint therebetween.

2. A water closet drain connection comprising a water closet having a deep annular groove in its base extending about and separate from its outlet, a drain pipe, a pipe section having a radial flange adapted to be secured to the floor and to the water 105 closet bowl, the upper end of said pipe section fitting closely within said groove in the closet base, a gasket supported only upon the upper end of the pipe section and compressed between the upper end of the pipe section and the bottom of said groove to 110 form a gas-tight joint therebetween, a collar formed upon the outside of the end of the drain pipe and forming therewith an upwardly facing annular groove, the lower end 115 of the pipe section fitting closely within the inside of said collar to form a tight joint therewith, and a poured metal seal filling the annular groove beneath the lower end of the pipe section and between it and the upper end of the drain pipe.

3. A water closet drain connection comprising a water closet having a downwardly facing deep annular groove about its outlet, a drain pipe, a pipe section having a radial flange adapted to be secured to the floor and 120

130

to the water closet bowl, the upper end of said pipe section fitting closely about the outlet of the water closet and within said groove, a gasket supported only upon the 5 upper end of the pipe section and compressed between the upper end of the pipe section and the bottom of said groove to form a gas-tight joint therebetween, and a connection between the lower end of said pipe section and the upper end of the drain 10 pipe comprising a tight joint between the pipe section and drain pipe, and an inside poured metal seal between said members and sealing said joint.

Signed at Seattle, Washington, this 13th 15 day of January, 1920.

JAMES A. JOHNSTON.
